(57) **CLAIM**

The ornamental design for a pet toy as shown and described.

DESCRIPTION

FIG. 1 is a top, front, right perspective view of a pet toy of my new design;

FIG. 2 is a bottom, rear, left side perspective view thereof;
FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof; and,

FIG. 9 is an exploded perspective view of the pet toy in FIG. 2, shown disassembled for completeness of illustration.
The broken lines in the drawings depict portions of the pet toy that form no part of the claimed design.

1 Claim, 9 Drawing Sheets
